UNITED STATES PATENT OFFICE.

JOHN D. PUFF, OF EAST ST. LOUIS, ILLINOIS.

BORING-MACHINE.

1,168,224.

Specification of Letters Patent. Patented Jan. 11, 1916.

Application filed September 10, 1912. Serial No. 719,642.

To all whom it may concern:

Be it known that I, JOHN D. PUFF, a citizen of the United States, and resident of East St. Louis, Illinois, have invented certain new and useful Improvements in Boring-Machines, of which the following is a specification.

This invention relates to improvements in boring machines and has for its object a plurality of horizontally arranged boring bits, a means for driving the bits forwardly, a plurality of vertically arranged boring bits, a means for advancing said bits upwardly, and a lever mechanism for simultaneously advancing the horizontal bits and raising the vertical bits.

A further object is to construct a boring machine which is designed to bore horizontal and vertical holes in barrel heads so that rods and fastening devices can be inserted through the holes for supporting the heads in position in the barrel.

A further object of my invention is to construct a machine with two sets of horizontally arranged boring bits, the same advancing forwardly simultaneously with its rotation, a means for automatically releasing one set of the bits so that it may return to its normal position in advance of the opposite set and vertically arranged bits for boring vertical holes simultaneously with the horizontal operation.

Figure 1 is a side front view of my improved boring machine. Fig. 2 is a top plan view of the same. Fig. 3 is an end view looking from the left of Fig. 1. Fig. 4 is a vertical sectional view taken on the line 4—4 of Fig. 2 and viewing the same in the direction indicated by the arrow on the line 4—4. Fig. 5 is a detail enlarged sectional view of the mechanism in which the vertical bits are supported and raised, the same taken on the line 5—5 of Fig. 4. Fig. 6 is an enlarged detail, horizontal sectional view of the belt and pulley mechanism by which the vertical bits are rotated, the same taken on the line 6—6 of Figs. 1 and 4. Fig. 7 is a detail top plan view of the sliding bearing made use of and which constitutes a part of the vertical bit supporting mechanism. Fig. 8 is a detail perspective view of one of the clamp arms

made use of for supporting the barrel head in position, a part thereof being broken away. Fig. 9 is a detail top plan view of the lever mechanism by which the horizontal bits are advanced. Fig. 10 is a detail side view of the lever mechanism by which the vertical bits are elevated. Fig. 11 is a top plan view of the same. Fig. 12 is a top plan view of a portion of a barrel head showing the bits in their operative position, a part thereof being broken away, one set of the bits having performed their function and returned to their normal position. Fig. 13 is a detail sectional view of a barrel showing the head therein and the rods and fastening devices used in the holes made by the boring machine for supporting the head in position.

The construction of my invention consists of a bed plate 14 mounted upon suitable standards 15; the said bed plate is provided with a plurality of grooves 16 extending the entire width of the bed plate, which accommodate projecting lugs 17 formed on the under surface of the tool plates 18 adjustably mounted on the bed plate, and on each of the tool plates are located journal boxes 19 and 20 in which the tool spindles 21 have bearing. On the spindles and between the journals 19 and 20 are mounted pulleys 22 which are keyed to the spindles so that rotation is imparted thereto yet providing free sliding movement of said spindles in the pulleys and journals, the purpose of which is to permit the tools or bits 23 supported in the chucks 24 formed on the end of the tool spindles to rotate as well as to be advanced forwardly to enter the material located on the material plate 25. On the tool plates are also provided guides 26, which have openings of proper diameter to permit the tools or bits to freely pass therethrough and to properly hold the tools or bits in alinement so that the holes bored thereby are absolutely true.

To the under surface of the bed plate is firmly attached a pair of depending brackets 27 and 28, and to the bottom ends thereof are pivotally attached lever arms 29, the upper ends thereof being bifurcated as indicated by the numeral 30 which straddle collars 31 located on the tool spindles 21 immediately

to the rear of the chucks 24; the bifurcated ends of the levers are suitably slotted as indicated by the numeral 32 so as to provide for free movement of the levers when advancing the tool spindles forwardly. The opposite ends of the tool spindles are provided with collars 33, and on said spindles between the collars and the end of the journals 20 are located springs 34 which have a tendency to return the spindles back to their normal position after the holes in the material have been bored.

The tool plates together with the guides, journals and tool spindles are adjustable laterally in the grooves 16 and are guided by means of the lugs 17 and are held in their adjusted position by means of the machine screws 35 passing through the slots 36 formed in the base plate and supported in the tool plates.

The material plate is formed integral with the base plate and at a raised position, the said plate being semi-circular in form (see Fig. 2), the sides provided with projections 37 against which the periphery of the material placed on the plate contacts. The straight edge of the plate is also provided with a projection 38, and in alignment with the straight edge is formed elongated slots 39 through which the vertical bits 40 operate; the construction and operation of which will be hereinafter fully described. On this material plate is located one-half of the barrel head, and the said material constituting the barrel head is held in clamped position on the plate by means of the clamping arms 41, which are pivotally attached at the point indicated by the numeral 42 to two of the tool plates, the opposite end having handles 43, by which the clamping arms are manipulated, and each of the arms have a bent projection 44 which contacts with the curved edge of the barrel head holding the same flat upon the plate, and preventing the same from bulging, the remaining portion of the arms contacting with a portion of the upper surface of the barrel head so as to lock the same against the plate preventing the same from being raised during the operation of the vertical bits 40 and a downward pressing movement of the clamping arms is accomplished by means of the guide bar 45 extending across the entire bed plate slidingly in advance of the straight edge portion of the material plate, the under surface being inclined as indicated by the numeral 46 (see Fig. 4).

The construction of all of the horizontal tool plates, and operating mechanism thereon is of identical structure and over the pulleys 22 are passed belts 47 and 48 by which the bits are properly rotated.

The forward movement of the bits is accomplished by a mechanism consisting of

rock arms 49, 50, and 51 all mounted upon a shaft 52 which is supported in hangers 53 secured to the under side of the bed plate. To the rock arm 49 is attached one end of the connecting rod 54 which is connected to a foot treadle 55. To the ends of the rock arms 50 and 51 are attached connecting rods 56 and 57, the opposite ends attached to the bifurcated levers 29, and by means of the downward pressure of the foot upon the treadle 55, the bifurcated levers are advanced forwardly bringing the bits in contact with the material forming a bore into the edge thereof.

The rock arm 50 is provided with an integral clutch collar 58 and is loosely mounted upon the shaft 52 and on said shaft is located a rigid collar 59 between which, and the rock arm 50 is a spring 60; the lever 51 is also provided with a clutch collar 61 and is rigidly secured to the shaft 52. The contacting surfaces of the collars 58 and 61 are toothed as shown and when the levers are operated the shaft 52 is partly turned, advancing all of the horizontal bits simultaneously until the rock arm 50 contacts with 90 and rides over an inclined surface 62 formed on the bottom end of a hanger bracket 63 suspended from the bottom of the material plate; by this action the lever after having advanced upon the inclined surface, the clutch members are released and the rock arm 50 will return to its normal position together with the pair of horizontal bits controlled thereby by means of the action of the coiled springs located on the left hand set of tool spindles. This operation removes the bits 64 after they have performed their function, and at a period prior to the completion of the forward movement of the bits 65, which bits will then continue to advance 105 boring through the material in direct alignment with the holes 66 already bored by the bits 64 continuing to cut through the material and in this manner prevents the points of both bits from contacting and making 110 the hole extend entirely through the board. The function performed by the horizontal bits is clearly shown in Fig. 12.

On the shaft 52 and near each end thereof is mounted a compound lever 67, which controls the vertical movement of the vertical bits; these compound levers are composed of a casting 68 rigidly secured to said shaft, the free end suitably recessed to accommodate the members 69 which are held in position by the bolt 70, each of these members provided with a tooth 71 which is designed to come in contact with the inclined surface 72 formed on the casting 68, the free ends being provided with elongated slots 73 through which project the lugs 74 formed on the collar 75 located around the vertical tool spindles 76 (see Fig. 5). During the

partial rotation of the shaft 52 the compound lever mechanism 67 first assumes the position as shown by dotted lines in Fig. 10 before the vertical bits are raised. After 5 the bits have been operated and the holes bored, the bits are returned to their normal position by means of the coiled springs located on the tool spindles.

The construction of the vertical bit mechanism is as follows: Suspended from the bed plates are brackets 77 and 78, the same being located side by side and bolted together (see Fig. 1); each set of brackets are connected together by cross-bars 79 and 80 15 provided with elongated slots 81 and 82. Through these slots are inserted machine screws 83, the threaded ends communicating with elongated projections 84 which form a part of the tool spindle bearing 20 85. The bearings are connected together by yokes 86. In these bearings is located a sleeve 87, this sleeve having a key 88 which operates in a keyway 89 formed in the two spindles 76 and on this sleeve between the 25 yokes 86 is a pulley 90 by which the tool spindle is rotated. The bottom end of the tool spindle is provided with a rigid collar 91 and between said collar and the bottom edge of the sleeve is a coiled spring 92 by 30 which the tool spindle is brought back to its normal position. The elongated projections 84 act as guides for the bearings and the same are supported in grooves 93 formed on the inner surface of the cross bars 79 and 35 80 (see Fig. 5), and by means of the elongated slots 81 and 82 the position of the vertical bits can be horizontally adjusted.

The horizontal cross bars 79 are provided with hubs 94 and 95 in which are located 40 shafts 96, these shafts being provided with horizontal pulleys 97, and on the opposite side of one of the cross bars is a bracket 98 on which an idle pulley 99 is mounted. Over these pulleys and the pulleys 90 operates a belt 100, this belt extending downwardly over a pulley 101 mounted on a line shaft 102 which is supported in bearings 103 located beneath the machine. On this line shaft is mounted pulleys 104 and 105 45 which operate belts 47 and 48 placing in rotation the pulleys 22 of the horizontal tool spindles and the machine is driven by means of the belt 106 from any source of supply.

The machine is constructed for the purpose of boring holes edgewise through the material forming the barrel heads so that rods may be inserted through the openings for fastening the heads into barrels, likewise to bore vertical holes so that fastening devices such as those indicated by the numeral 107 shown in Fig. 13 can be inserted and the 50 operation of my invention is as follows: The material to be bored is placed on the material plate which as shown in Fig. 2 is

semi-circular for the purpose of boring barrel heads but the said plate can be constructed rectangular so that box tops can be similarly bored. The material after being placed in position on the plate is clamped in position by means of the clamping arms 55 65 pressed inwardly by means of the handles 43; the operator then by pressing downwardly on the foot treadle 55 operates the lever mechanism on the shaft 52 advancing the bifurcated levers forwardly conveying 70 with them the rotating bits 64 and 65; the position of the bits is such, and by means of the clutch mechanism on the shaft 52 the bits 64 are advanced in the material their proper length and are automatically released 75 before the bits 65 continue their forward travel in order to meet the opening formed by the bits 64. During the movement of the shaft 52 the compound lever mechanism is operating to a position as 80 shown by dotted lines in Fig. 10 and at the moment of the release of the bits 64, the vertical bits are raised to bore the vertical 85 holes in the straight edge of the material and by the release of the foot treadle the 90 entire mechanism is brought back to its normal position by the expansion of the coiled springs on the various tool posts.

Having fully described my invention what I claim is:

1. A boring machine comprising a bed plate mounted upon standards, tool plates laterally adjustably mounted on the bed plate, a material plate located on the bed plate between the tool plates, tool spindles 95 mounted in bearings carried by the tool plates, bifurcated levers connected to the tool spindles by which the same are advanced forwardly bringing the bits carried thereby in contact with the edge of the material to be bored, pivoted spring clamping arms for supporting the material on the material plate, two vertical tool spindles suspended beneath the bed plate and adjustably mounted and means for elevating the same 100 at a proper period to bore vertical holes in the material and a clutch mechanism by which one set of the tool spindles is automatically released in advance of the other set, the other set continuing forward making one continuous hole through the material, and means for releasing and automatically returning all of the bits to their starting position.

2. A boring machine comprising a plurality of horizontally arranged rotating and adjustable spindles, bits carried thereby for boring holes through the edge of the material located between the bits, a pair of rotating adjustably mounted vertical spindles, 120 bits carried thereby and arranged to bore vertical holes in the material, and a rock arm mechanism for advancing the bits in 125

contact with the material, a clutch for automatically releasing one set of the horizontal bits in advance of the other so as to prevent the point of the bits from contacting 5 during their operation, substantially as specified, and means for returning the remaining bits to their starting position.

In testimony whereof, I have signed my name to this specification, in presence of two subscribing witnesses.

JOHN D. PUFF.
